UNITED STATES PATENT OFFICE.

SAMUEL WEISGLASS, OF BROOKLYN, NEW YORK.

CRIB CORNER LOCK.

Application filed January 4, 1922. Serial No. 526,893.

To all whom it may concern:

Be it known that I, SAMUEL WEISGLASS, a citizen of the United States, residing in Brooklyn, in the county of Kings and State of New York, have invented certain new and useful Improvements in Crib Corner Locks, of which the following is a specification.

The principal object of this invention is to provide a bed or crib of particularly simple and rigid construction.

Another object is the means provided by which the side rails may be quickly attached to or detached from the head and foot frames.

A further purpose is to provide a side rail securing device of practically flat construction, avoiding the unsightly and unsanitary projecting features usual in the structures of this character.

These and other similar objects are attained by the novel construction and arrangement of parts as hereinafter described and shown in the accompanying drawings, forming a material part of this disclosure, and in which:

Figure 1 is a perspective view of a crib embodying this invention.

Figure 2 is a fragmentary perspective view of a frame or leg element showing the attaching members.

Figure 3 is a partial sectional, partial side elevational view of attaching members in locked position, taken on the line 3—3 of Figure 4.

Figure 4 is a sectional view of the same taken on the line 4—4 of Figure 3.

Referring to the drawings in detail, the numerals 5 and 5' represent bent square tubular elements comprising with the tubular cross bar elements 6 and 6' the main head and foot frame members of the structure.

Horizontal tubular elements 8 and 9, connected by the vertically disposed tubular elements 10 form side frames which, being pierced near their extremities by annular openings, are adapted to engage with and are slidably controlled by the guide bars 12 secured in vertical position by the lugs 13 attached to the inside faces of the frame elements 5 and 5'.

Catches 15 are provided allowing the side frames to be dropped as shown at A in Figure 1 or locked in raised position as at B in same figure.

A pair of rolled angles constituting spring supporting side rails 18, have secured upon

their outer ends, by the rivets 19, the angularly bent locking members 20 comprising a fork containing a slot 21 and tapered wedge element 22 adapted to be engaged and rigidly secured within a socket 25.

These sockets each comprise base elements 26 provided with angularly indented openings 27 receptive of the flat head attaching screws 28, a front or clamp element 29, an edge wall 30 integral with the base 26 and the clamp element 29 and angularly formed in a manner adapted to engage and agree throughout its length with the wedge element 22.

Re-enforcing plates 32 provided with screw-threaded openings, are positioned adjacent the inside walls of the leg portions of the frames 5 and 5' and are secured thereto by the attaching screws 28, passing through the socket base 26, the bevelled projections 27 acting as dowels in openings provided in the frames 5 and 5'; the screws engaging with screw-threaded holes formed in the plates 32, thus producing a re-enforced socket attaching means of great strength.

Clamp screws 35, passing freely through openings in the sockets 25 are screw-threaded within the plates 32, so that when assembled, the outer side wall of the slot 21 of the locking member 20, abutting against the clamp screws 35, forces the wedge element 22 against the inner face of the wall 30, wedging itself therein; further rigidity is secured by tightening the clamp screw 35.

Referring to Figure 2, it will be understood that the unit members 20 and 25 must be fabricated with opposite bends forming pairs of right and left hand constructions.

I do not wish to limit the application of my invention to cribs, but anticipate its employment on beds, couches, chairs and other structures adapted to be separated into distinct units.

Having thus described my invention and set forth the manner of its construction and use, what I claim as new and desire to secure by Letters Patent, is:

1. In side rail and post connections, a socket open at top and bottom and one side and comprising a base plate secured to a face of the post, and a resilient face plate connected along one side thereof to the base plate and extending thereover in spaced relation therefrom, the face plate having a centrally disposed aperture therethrough; adjustable supporting means passing through

said aperture and through a registering aperture in the base plate and engaging the post; and a locking member operatively connected to the side rail at an end of the rail having a portion receivable between the base plate and face plate and arranged for straddling said supporting means for vertical support; lateral movement of the locking member when so received being prevented 10 by engagement of one side thereof with said connecting side of the face plate; the face plate being compressible by adjustment of said supporting means for clamping the locking member in locking position.

15 2. In side rail and post connections, a socket open at top and bottom and one side and comprising a base plate and a resilient face plate connected along an inturned side thereof to the base plate and extending 20 thereover in spaced relation therefrom, the face plate having a centrally disposed aperture therethrough; a reinforcing plate arranged on the inner side of the post in opposed relation to the base plate; means for 25 securing the base plate and reinforcing plate to the post; adjustable supporting means passing through said aperture and through registering apertures in the base plate and post and engaging the reinforcing plate; 30 and a locking member operatively connected to the side rail at one end of the rail having a portion receivable between the base plate and face plate and arranged for straddling said supporting means for vertical support; 35 lateral movement of the locking member when so received being prevented by engage-

ment of one side thereof with the inturned side of the face plate; the face plate being compressible by adjustment of said supporting means for clamping the locking member 40 in locking position.

3. In rail and post connections, a socket having annular tenons in its base engaging openings in the post, flat head screws passing through said tenons into the post, the outer element of the socket being connected along one longitudinal edge only, a plate bent at a right angle, one of the angular elements being rigidly united to the end of the rail and the other containing a slot open at its 50 lower edge, said slotted element being suited to enter said socket, and means in said socket adapted to engage in the slot, said means also being capable of clamping the last named element firmly within the socket. 55

4. In rail and hollow post connections, a socket comprising a flat base, a re-enforcing plate within said post, tenons extending into the wall of the post, securing means engaging the base to said plate through the wall 60 of the post, an outer wall connected with said base along one edge, a screw passing through the outer wall into said plate, said screw being capable of springing said outer wall toward the base, a forked element disposable on said screw between said wall and base, and an arm formed with said element fixed to said rail. 65

SAMUEL WEISGLASS.
